MANUALLY PROPELLED WATER CRAFT

Gerald Martin, 595 NW. 91st St.,
Miami Beach, Fla.

Filed Apr. 11, 1973, Ser. No. 350,069

Term of patent 14 years

Int. Cl. D12—06

U.S. Cl. D12—68

FIG. 1 is a top view of a manually propelled water craft showing my new design;

FIG. 2 is a bottom view thereof;

FIG. 3 is a side elevational view thereof; and
FIG. 4 is a front elevational view thereof.

I claim:

The ornamental design for a manually propelled water craft, as shown and described.
